US0D1089037S

(12) **United States Design Patent** (10) Patent No.: **US D1,089,037 S**
(45) Date of Patent: **** Aug. 19, 2025**

(54) **SCREW PROPELLER**

(71) Applicant: **GUANGDONG EPROPULSION TECHNOLOGY LIMITED**,
Dongguan (CN)

(72) Inventor: **Xing Li**, Guangdong (CN)

(**) Term: **15 Years**

(21) Appl. No.: **35/522,685**

(22) Filed: **Oct. 16, 2023**

(80) **Hague Agreement Data**

Int. Filing Date: **Oct. 16, 2023**

Int. Reg. No.: **DM/232766**

Int. Reg. Date: **Oct. 16, 2023**

Int. Reg. Pub. Date: **Oct. 18, 2024**

(51) **LOC (15) Cl.** **12-16**

(52) **U.S. Cl.**

USPC **D12/214**

(58) **Field of Classification Search**

Assistant Examiner — Cleso Moore, Jr.

(57)

CLAIM

The ornamental design for screw propeller as shown and described.

DESCRIPTION

3. Screw propeller

3.1: Perspective

3.2: Perspective

3.3: Front

3.4: Back

3.5: Left

3.6: Right

3.7: Top

3.8: Bottom

The design is a product configured for rotation to generate propulsion.
